UNITED STATES PATENT OFFICE.

EDWIN ALLEN, OF GALESBURG, ILLINOIS, ASSIGNOR OF ONE-HALF TO EDWARD J. KING, OF GALESBURG, ILLINOIS.

GATE FASTENER.

Application filed November 1, 1920. Serial No. 420,885.

To all whom it may concern:

Be it known that I, EDWIN ALLEN, a citizen of the United States, residing at Galesburg, in the county of Knox and State of Illinois, have invented a certain new and useful Improvement in Gate Fasteners, of which the following is a full, clear, concise, and exact description, reference being had to the accompanying drawings, forming a part of this specification.

This invention relates to improvements in gates.

One object of the invention is to provide a simple and efficient gate of the swinging type which is so arranged as to be automatically unlatched and opened by driving a vehicle, such as an automobile, thereagainst and without the necessity of the driver or other occupant of the vehicle descending to the ground to release the gate.

A more specific object of the invention is to provide a swinging gate of the character above indicated which is further characterized by means arranged to automatically 25 turn the gate to closed latched position after the vehicle has passed; and by means arranged to prevent the gate being accidentally released and opened by hogs, cattle or other animals.

In the drawing forming a part of this specification, Figure 1 is an elevational view of a gate showing my improvements in connection therewith. Figure 2 is a top plan view of the structure illustrated in Figure 1. Figure 3 is an end elevational view of the gate, the figure being upon a somewhat enlarged scale and illustrating also the manner in which the gate is unlatched or released. Figure 4 is a broken, elevational view similar to Figure 1 illustrating another embodiment of the invention. And Figure 5 is a detail horizontal sectional view corresponding substantially to the line 5-5 of Figure 4.

In said drawing and referring first to Figures 1, 2 and 3, a pair of gate posts is indicated at 10 and 11, spaced in the usual manner to define the gate opening of desired width. The post 10 is provided with a rigid vertically elongated pivot or hinge pin 12 suitably united to the post 10 as indicated. The gate proper is indicated at 13, the same being shown as comprising a plurality of horizontally extending spaced slats 14-14, upright braces 15-15 in the form

of angle irons, and diagonal braces 16-16. The gate shown is of the so-called non-sagging type but, as will be understood by those skilled in the art, the type of gate and its construction may be varied as desired without departing from the spirit of the invention. The gate 13 is swingably mounted on the hinge or pivot bar 12 by a pair of hinge straps 17-17, it being obvious that the latter are so located as to permit the gate to rise on the pivot bar 12.

On the other post 11 opposite the free end of the gate, is secured a casting or plate 18 notched on its upper face as indicated at 19. The plate 18 has its upper edges 20 curved on opposite sides of the notch 19 as indicated at 20-20 so that said edges 20 are adapted to act as elevating cams for the free end of the latch bar 21 which is pivotally mounted on the gate 13 at the point indicated at 22. The latch bar 21 is preferably of the same width as the slats 14 and is vertically guided between the upright braces 15-15 which are applied to opposite sides of the slats, as clearly indicated in Figures 1 and 3. With the construction of plate 18 and latch bar 21 above described, it is evident that, as the gate swings to normal closed position, the latch bar will be elevated by the cam edges 20 and finally seat itself in the notch 19, thereby locking the gate in closed position.

To effect the release of the gate latch, I employ an elongated rod or shaft 23 which is rotatably supported at its ends in suitable bearing brackets 24-24 secured to the gate. At the end of the shaft 23 corresponding to the free end of the gate there is secured a vertically upstanding lever 25 having a pair of diverging fingers 26-26 at its upper end, the latter having camming edges 27-27 so disposed that, as the lever 25 is swung upon oscillation of the shaft 23, either one of the fingers 26 will cam or elevate the latch bar 21 upwardly sufficiently to clear the notch 19. At the point of the latch bar engaged by the lever 25, a wear plate 28 is preferably secured to the latch bar.

The shaft 23 has rigidly secured thereto near its ends members 29-29 each of which is formed with a pair of oppositely extended arms 30-30. The arms 30 are bent outwardly and downwardly as clearly shown in Figure 3 and at their lower ends extend in

a nearly vertical direction as indicated at 31—31. On each side of the gate proper is secured to the portions 31, a horizontally extending relatively wide bumper board or bar 32. The boards or bars 32 are made of a length greater than the usual gauge of automobiles, trucks and like vehicles and are located approximately at a level corresponding to the axles, as indicated in Figure 3 10 where a wheel is diagrammatically illustrated by dotted lines at 33. With the construction just described, it is evident that the wheels of a vehicle engaging the boards or bars 32, on either side of the gate, will 15 compel oscillation of the shaft 23 and the latter in turn will effect release of the latch bar 21 through the double-acting cam lever 25. After the release of the latch, as the vehicle continues to push against the gate, 20 the latter will be swung about its vertical pivot as will be obvious. The bars or boards 32 are also preferably made sufficiently wide to insure the bumpers, if any, and the usual automobile running boards engaging the 25 faces thereof and to prevent possibility of running boards or other projecting parts of the automobiles engaging any other part of the gate while the vehicle is passing through the gate opening.

30 In connection with the latch bar 21, I employ an adjustable spring device in order to prevent accidental release of the latch by cattle, hogs, or other animals pushing against the bars or boards 32. In the construction 35 shown, I employ a plate spring 34 which bears on the upper side of the latch bar 21. One end of said spring 34 is preferably attached on a pin 25 between two of the uprights 15. The other end of the spring 34 40 is attached as indicated at 36 to a shackle 37 which is vertically adjustably mounted, as by means of a pin and a series of openings, to one of the slats 14. As will be evident, by adjusting the shackle 37, the spring pressure on the latch bar 21 may be varied so as 45 to prevent the latch bar from being released by any comparatively light pressure exerted against the bumper boards 32. As will be obvious to those skilled in the art, various 50 other devices may be employed to regulate the amount of pressure required to release the latch.

55 In order to insure the return of the gate to normal closed position, after the vehicle has passed through the opening, I may use the following arrangement. Secured to the post 10 is a plate 39 having a substantially circular double cam track 40—40, the lowest portions of the track being in line with the 60 gate when the latter is in closed position. Secured to the slat 14 of the gate immediately adjacent the plate tracks 40, is a bracket 41 carrying an anti-friction roller 42 which is adapted to ride upon the track 40 65 as the gate swings. As will be obvious, as

the gate swings to either side of normal closed position, the gate will be vertically elevated on its pivot pin or bar 12 and consequently, after the vehicle has passed by the gate, the latter will be returned automatically to its closed position under the influence of gravity. 70

In Figures 4 and 5, a somewhat different construction is illustrated which is preferable under some conditions. As shown in 75 said Figures 4 and 5, a vertical pivot pin or bar 112 is employed, secured to the post 110 in any suitable manner and the gate is vertically adjustably mounted on the opposite bar 112 by means of hinge straps 117—117, 80 each of which carries a grooved anti-friction roller 50 and 51, respectively. The roller 50 carried by the upper hinge strap 117 is located on the side of the hinge bar 112 remote from the gate and the roller 51 is carried by the lower hinge strap 117 between the gate and the hinge bar. This is done in consideration of the fact that the weight of the gate will exert a pull toward the left at 85 the top and push inwardly at the bottom toward the right, as viewed in Figure 4 and as will be understood by those skilled in the art. In this construction I locate the double elevating cam track 140 at the bottom, the same being preferably supported on a suitable bed of concrete 52, or other foundation. In view of the different location of the cam track, the corresponding anti-friction roller 142 is located at the bottom of the gate, said roller being carried by a track 100 141 secured to the lower slat of the gate. The operation of the gate will be the same as that hereinbefore described in connection with the gate shown in Figures 1 to 3. It will also be understood by those skilled in the 105 art, that other means may be employed to insure the swinging return of the gate to closed position.

I have herein shown and described what I now consider the preferred manner of carrying out the invention, but the same is merely illustrative and I contemplate all changes and modifications that come within the scope of the claims appended hereto. 110

115 I claim:

1. In a gate structure, the combination with upright elements defining the gate opening and a gate proper hinged at one of its ends to one of said elements to swing about a vertical axis; of releasable locking 120 means for the gate; means arranged to be operated by a vehicle wheel, said means being pivoted about a horizontal axis and provided with vehicle wheel contacting elements rigid therewith extended to both sides 125 of the gate, the free ends of said elements being normally spaced from the gate proper, a distance sufficient to allow full operative movement of the pivoted means and adapted to be engaged directly by the ve- 130

- hicle wheel and moved inwardly toward the gate prior to a possibility of the vehicle wheel engaging the gate proper on either side; and devices interposed between said 5 pivotally mounted means and said locking means operable to release the latter upon actuation of said pivotally mounted means.
2. In a gate structure, the combination with upright elements defining the gate 10 opening and a gate proper hinged at one of its ends to one of said elements to swing about a vertical axis; of a notched locking plate secured to the other of said elements; a latch bar pivotally mounted on the gate proper to move in a vertical plane and adapted to cooperate with said plate to lock the door in closed position; means extended laterally from the side of the gate adapted to be operated by a vehicle wheel prior to 15 the possibility of the vehicle wheel engaging the gate proper, said means being movable toward and from the gate proper; and devices interposed between said movable means and the pivoted latch bar operable to 20 elevate the latter from the locking plate.
3. In a gate structure including a gate proper, pivotally mounted, the combination with a releasable locking means for said gate; movable means extended laterally 25 from the side of the gate at a level to be engaged by and operated by a vehicle wheel prior to the possibility of the vehicle wheel engaging the gate proper, devices interposed between said movable means and the locking means operable to release the latter upon 30 said movable means being actuated by the vehicle wheel; and adjustable means for regulating the amount of force required to actuate said releasable locking means.
4. In a gate structure, the combination 35
- with spaced gate posts and a gate proper; of means for pivotally mounting said gate proper to one of said posts, a latch plate secured to the other of said posts; a latch bar pivotally mounted on the gate proper; 40 adjustable means governing the force required to actuate the latch bar; a shaft pivotally mounted on the gate proper; horizontally extending wheel-engageable bars on opposite sides of the gate proper and rigidly associated with said shaft whereby the latter is adapted to be oscillated when either of said bars is engaged by a vehicle wheel; and a double acting cam lever carried by said shaft cooperable with said latch bar to release the latter from the latch plate. 45
5. In a gate structure; the combination with spaced gate posts and a gate proper; of means for pivotally mounting said gate proper to one of said posts to swing about 50 a vertical axis; a latch plate secured to the other of said posts; a latch bar pivotally mounted on the gate proper and cooperable with said plate; a shaft pivotally mounted on the gate proper; horizontally extending wheel-engageable bars on opposite sides of the gate proper and rigidly attached to said shaft whereby the latter is adapted to be oscillated when either of said bars is engaged by the vehicle wheel; and a double acting cam lever carried by said shaft cooperable with said latch bar to release the latter from the latch plate. 55

In witness that I claim the foregoing I have hereunto subscribed my name this 18th 60 day of Oct., 1920.

EDWIN ALLEN.
